DOUBLE TWIST TWISTING SPINDLE

Otto Bochmann and Wilhelm Lenk, Remscheid-Lennep, Germany, assignors to Barmer Maschinenfabrik Aktiengesellschaft, Wuppertal-Oberbarmen, Germany

Application February 17, 1932, Serial No. 593,573
In Germany July 3, 1931

8 Claims. (Cl. 117—23)

This invention relates to a double twist twisting spindle, in which the thread is drawn from the stationary unwinding spool, conducted through the hollow twisting spindle and over a 5 thread guiding element to the winding spool.

In the known twisting spindles of this type the thread guiding element is arranged on the spindle so that it participates in the rotation thereof. However, in order to prevent the thread running over the thread guiding element to the winding spool from coming into contact with the unwinding spool during the twisting, the thread guiding element must be of a certain diameter. Consequently, such a spindle has heavy rotating 10 masses which consume a great deal of power, so that the spindles are very expensive in use. Moreover, the rotating thread guiding element causes a strong air movement which either 15 renders the operation of the machine very difficult or must be deflected towards the inner side by special devices making the machine more expensive. Moreover, in the case of the rotating guiding element the spool holder carrying the unwinding spool is held in its inoperative position 20 by a weight rigidly mounted thereon. However, owing to the positive mounting of the spool holder one sided wear occurs at the inner bearing points so that they only possess a short life.

These disadvantages are overcome by the invention which consists in that a hollow thread guiding body is loosely mounted on the spindle and consequently does not participate in the rotating movement thereof. The thread guiding body may be domed or conical. In order to prevent 30 the thread from rubbing against the stationary edge of the guiding body when leaving the twisting spindle, it is advisable for the lower edge of the thread guiding body, stationary on the revolving spindle, to be covered by the upper edge of the thread storage ring with the twisting spindle. In this arrangement the thread guiding body is so dimensioned that fine to medium threads which can be worked with a small balloon can be dealt with on this arrangement. If 40 however coarse thread is to be worked, an insert body corresponding to the diameter of the larger unwinding spool owing to the thicker thread is placed in the stationary thread guiding body. In this arrangement of the thread guiding body the weight is arranged in the interior thereof, but for holding the unwinding spool 45 stationary the weight is only loosely inserted or loosely suspended on a holder or on a disc covering the guiding element. In the first instance

it is preferable, in order to avoid disturbing noises occurring owing to the vibrations of the machine, to provide a resilient mounting by elastic material, such as springs or the like.

The invention presents the advantage that, owing to the thread guiding body remaining stationary, the power required is reduced by one half, as the rotating masses are themselves reduced, but above all because these are approached as far as possible towards the turning axis of the spindle, so that a considerable cheapening in the running of these spindles is obtained. As the thread guiding body no longer participates in the rotation, no air movement is caused so that the attendance of the machine is in no way hindered and no special devices adding to the cost of the machine are necessary for deflecting the air movement. A further advantage consists in that, owing to the thread guiding body being stationary, the weight designed for holding stationary 10 the spool holder carrying the unwinding spool 15 can be loosely suspended or loosely inserted so that it does not hold the thread guiding body and consequently the spool holder in a certain position, these elements being adapted to move and 20 turn freely within certain limits. By this means 25 however any one sided wear of the bearings is avoided so that their life is considerably prolonged. It is true that both parts are prevented by the loose weight with the spindle from directly rotating, as this weight causes a continual 30 braking in opposite direction.

Several embodiments of the invention are illustrated by way of example in the accompanying drawings in which:

Figs. 1, 2, 3, and 4 show each in longitudinal section of one form construction of the twisting spindle.

Fig. 5 is an end view of Fig. 4 seen from the right.

Fig. 6 shows in longitudinal section a fifth 40 form of construction.

Fig. 7 is an end view of Fig. 6, seen from the right.

Fig. 8 shows in longitudinal section a modification of the form of construction of the twisting 45 spindle shown in Fig. 6.

Fig. 9 shows in longitudinal section a form of construction of a double twist twisting spindle.

Fig. 10 is an end elevation of Fig. 9 seen from 50 the right.

A spool holder 3 carrying the unwinding spool 2 is mounted on the hollow spindle. The thread 4 is guided from the unwinding spool 2 through the twisting spindle 1 to the thread storing ring 55

5 regulating the thread tension and passes from this ring to the winding spool. On the spool holder 3 a hollow thread guiding body 7, stationary with the spool holder, is arranged on a disc 6, the lower edge of which body extends over the thread storing ring 5 and thus prevents the stored thread from slipping off on to the spindle. The disc 6 carries in its interior a weight 8 for holding stationary the spool holder 3 (Fig. 1). The storing ring 5 may however be so constructed that its peripheral edge 5' covers the lower edge of the thread guiding body 7 stationary on the revolving spindle 1 (Fig. 2). In order to work coarser threads, an insert body 9 may, as shown in Fig. 3, be placed in the thread guiding body 7 in order to keep the circulating thread away from the unwinding spool which is larger in this instance. Owing to this measure exchanging of the thread guiding body 20 in accordance with the size of thread is no longer necessary. To avoid one sided wear of the bearings within the spool holder 3, it is advisable to loosely insert the weight 8, so that it leaves a certain freedom of movement to the thread guiding body 7 and therefore the spool holder 3, whereby a uniform wearing of the bearings and consequently a longer life is obtained (Figs. 4 and 5). The weight 8, as already mentioned, may either be loosely inserted (Fig. 4) or suspended on a holder 10 (Fig. 6) or on a disc 11 (Fig. 8) covering the guiding body 7, it being evident that both the holder 10, and the covering disc 11 are not rigidly connected to the spool holder 3. It is advisable, in order to prevent disturbing noises in the case of the loosely inserted weight 8, to resiliently support same by elastic means which however do not in any way hinder the free movement (Figs. 9 and 10). In this instance the weight may have recesses 12 in which spring controlled bolts 13 are arranged and pressed against the wall 6 and thus resiliently support the weight 8 against any vibrations which may occur.

We claim:—

45 1. A double twist twisting spindle, comprising in combination with the rotary spindle, a hollow thread guiding body loosely mounted on said spindle and adapted to rotate in either direction independently thereof, and a thread storing ring 50 formed on said rotary spindle and having an edge covering the adjacent edge of said hollow thread guiding body.

55 2. A double twist twisting spindle, comprising in combination with the rotary spindle, a spool holder mounted thereon, a hollow thread guiding body loosely mounted on said spool holder and adapted to rotate in either direction independently of the spindle, an unwinding spool fixed on said spool holder, and an insert body adapted 60 to be inserted in said thread guiding body for particularly large unwinding spools to keep the circulating thread away from said spool.

65 3. A double twist twisting spindle, comprising in combination with the rotary spindle, a spool holder mounted thereon, a hollow thread guiding body loosely mounted on said spool holder and adapted to rotate in either direction independently of the spindle, an unwinding spool in said spool holder, and a weight loosely inserted in 70 said hollow thread guiding body adapted to

prevent said hollow thread guiding body from participating in the rotary movement of said spindle.

4. A double twist twisting spindle, comprising in combination with the rotary spindle, a spool holder mounted thereon, a hollow thread guiding body loosely mounted on said spool holder and adapted to rotate in either direction independently of the spindle, and a weight loosely inserted in said hollow thread guiding body adapted to prevent said holder and said guiding body from participating in the rotary movement of said spindle. 10

5. A double twist twisting spindle comprising in combination with a rotary spindle, a stationary spool holder, a non-rotatable hollow thread guiding body fixed to the spool holder at the inner end thereof and loosely mounted on said spindle coaxially therewith and in the plane thereof whereby the spindle may rotate in either direction independently of the spool holder and hollow thread guiding body, an unwinding spool on the holder and a weight suspended in said hollow thread guiding body. 15

6. A double twist twisting spindle comprising in combination with a rotary spindle, a stationary spool holder, a non-rotatable hollow thread guiding body fixed to the spool holder at the inner end thereof and loosely mounted on said spindle coaxially therewith and in the plane thereof whereby the spindle may rotate in either 20 direction independently of the spool holder and hollow thread guiding body, an unwinding spool on the holder and a weight suspended in said hollow thread guiding body, a disk loosely mounted on the holder within the thread guiding body 25 and a weight suspended on said disk.

7. A double twist twisting spindle comprising in combination with a rotary spindle, a stationary spool holder, a non-rotatable hollow thread guiding body fixed to the spool holder at the inner end thereof and loosely mounted on said 30 spindle coaxially therewith and in the plane thereof whereby the spindle may rotate in either direction independently of the spool holder and hollow thread guiding body, an unwinding spool on the holder and a weight suspended in said hollow thread guiding body, an unwinding spool on said holder, a weight loosely inserted in said 35 hollow thread guide body and resilient means carried by the spool holder adapted to support said weight without impairing its freedom of 40 movement.

8. A double twist twisting spindle comprising in combination with a rotary spindle, a stationary spool holder, a non-rotatable hollow thread guiding body fixed to the spool holder at the inner end thereof and loosely mounted on said 45 spindle coaxially therewith and in the plane thereof whereby the spindle may rotate in either direction independently of the spool holder and hollow thread guiding body, an unwinding spool on the holder and a weight suspended in said hollow thread guiding body, an unwinding spool on said holder, a weight loosely inserted in said 50 hollow thread guide body and spring loaded bolts within the thread guide body adapted to support said weight without impairing its freedom of 55 movement.

OTTO BOCHMANN.
WILHELM LENK.
